UNITED STATES PATENT OFFICE

2,233,054

BUILDING STRUCTURE

Arthur A. Heeren, Chicago, Ill., assignor to United States Gypsum Company, Chicago, Ill., a corporation of Illinois

Application May 27, 1939, Serial No. 276,051

4 Claims. (CL 72—71)

This invention relates to building structure, and more particularly to roof and floor structures and the elements incorporated therein in which the structure is substantially self-supporting, and may comprise, among other elements, preformed or precast tile ordinarily made of any suitable material such as gypsum and the like. The invention also contemplates a building structure of the monolithic type which may suitably be reinforced and in which plaster boards, cement, gypsum, and the like may be used to form a substantially rigid monolithic structure.

It is an object of the invention to provide a structure of the character described which may easily be assembled and in which all of the elements will be retained in their proper relationship during construction of the floor or roof, and in which certain elements of the structure are so formed and related to the other elements associated therewith that dust pockets will be entirely eliminated. Floors and the like of the type disclosed herein are ordinarily provided with panel-supporting members in the form of elongated flanged bars with preformed tile panels having their marginal edges supported on the flanges and extending between the bars.

Heretofore, bars or strips have been used which were substantially in the form of I-bars or the like, in which the upper flanges were somewhat narrower than the lower or base flanges, and in which the tile or panels were supported by resting their marginal edges on the lower flanges. However, in these prior constructions the lower flanges varied in thickness from the web to the outer edge and thereby provided an angular or sloping upper surface usually having an angle of about 4° toward the outer edge of the flange. In such constructions, when the panels were positioned on the flanges, the panels were supported only on the corners thereof; that is, the edge corners of the panels rested on the flange adjacent the web, and an elongated dust pocket was formed between the outer edge of the flange and the panel.

Dust pockets are very objectionable, particularly in certain factory constructions, as the accumulated dust under certain conditions will cause explosions or other serious results. The present invention contemplates a structure in which dust pockets are entirely eliminated and in addition various improvements are made to provide for easy assembly of the structure and to improve the efficiency of the structure after it is completed.

It is a further object to provide a panel supporting bar or strip which for convenience herein will be called a bulb-T member, and which is adapted to locate the panels relative to the bulb and to each other in such a manner as to maintain accuracy in the finished structure and to provide convenient means for sealing the spaces between adjacent panels and between the panels and their associated bulb-T member.

The invention also contemplates a bulb-T supporting strip particularly adapted for monolithic structures whereby plaster board or the like may easily and conveniently be located in spaced relation on the supporting bulb-T's, and will accurately retain their spaced relationship during and after construction of the floor or roof.

Further objects will be apparent from the specification and the appended claims.

In the drawing—

Fig. 1 is a fragmentary perspective view partially in section of a roof or floor structure illustrating one embodiment of the invention.

Fig. 2 is a transverse sectional view through one of the bulb-T's illustrated in Fig. 1.

Fig. 3 is a transverse sectional view through the embodiment illustrated in Fig. 1 and taken on a line substantially corresponding to line 3—3 of Fig. 1, and

Fig. 4 is a transverse sectional view similar to that shown in Fig. 3, but illustrates an embodiment comprising a monolithic floor or roof structure employing the same bulb-T strips as shown in the other views.

Referring to the drawing in detail, the embodiment illustrated comprises a floor or roof supported on purlins 1, which may be of any suitable type, preferably in the form of I-beams, as shown. Special steel strips 2 are transversely supported on the purlins 1 in spaced relation and may be secured thereto by means of welding or clipping as at 3. These strips 2 comprise the bulb-T's previously mentioned, a transverse sectional view through one of these strips being illustrated in Fig. 2.

The bulb-T strip 2 comprises a wide and thin base 4 forming wide flanges 5 which extend laterally from a central vertical web 6. The web 6 terminates in a so-called bulb portion 7 which may be of any suitable shape, but is preferably substantially rectangular, as shown. The bulb and base are of such relative dimensions that the center of gravity of the strip is substantially midway of the vertical dimension of the strip and in the vertical axial plane. The bulb-T strip is

provided, adjacent the intersections of the base, with filletlike portions or ribs 8, that is, the base is materially thickened in the corners formed by the intersection of the base and web. The outer edge of these fillets or ribs form elongated shoulders 9, which are preferably so positioned that the over-all distance between the two opposed shoulders is somewhat greater than the width of the bulb 7. This is clearly shown in 10. Fig. 3.

In building the structure shown in Figs. 1 and 3, after the bulb-T strips are secured in position, precast panels or tile 10, preferably of gypsum, are positioned between the strips, as shown, 15 with their lower marginal edges resting on the laterally extending flanges of opposed pairs of bulb-T strips.

It will be noted that the upper surface of each flange is perpendicular to the web, and therefore the outer marginal edges of the tiles rest snugly on the entire area of the flanges and may contact the entire surface thereof. And particularly, the bottom surface of the panel engages the outer marginal edge of the flange in 25 such a manner that the joint therebetween is sealed and dust pockets can not be formed between the panel and flange. It should especially be noted that when the panels are placed upon the flanges 5, they are accurately located between the bulbs 7 and uniformly spaced therefrom. This is important as the accurate alignment of the panels greatly improves the appearance of the structure and also provides a space 11 between the bulb and each panel, 30 whereby a sealing material 12, which is preferably a grout-like cementitious plastic, which is in more or less fluid form, is poured into the interstices between the panels and may flow downwardly around the bulbs and web and may 40 fill the spaces 12 in the manner shown. The lower edges 13 of the bulb provide shoulders whereby the entire structure is interlocked when the grout 12 sets.

The shoulders 9 on the base 4 may of course 45 be positioned as desired and in accordance with requirements, an important consideration being that these shoulders may accurately locate the panels, particularly with respect to the bulb 7, and they may also greatly strengthen the intersection between the web and the base.

Fig. 4 illustrates an embodiment in which the same bulb-T members may be used in the construction of a so-called monolithic floor or roof. In this embodiment plaster board 14 or the like 55 is supported on the flanges 5 in the same manner as the precast panels 10 previously described. These plaster boards are located with respect to each other and to the bulb-T strips by means of the shoulders 9. A reinforcing element 15 is 60 provided and is suspended on the bulbs 7 substantially as illustrated so that depending arcuate portions are formed between the bulb-T strips. The reinforcing element 15 may comprise a sheet of wire mesh or expanded metal, or any suitable foraminated element. A suitable cementitious material 16 may then be poured over the structure so as to form a single slab somewhat greater in thickness than the height of the bulb-T's. This material binds with the 70 plaster board and when the cementitious material sets it will be supported on the bulb-T strips by means of the reinforcing element 15, and will also be supported on the bases 4 in the manner illustrated.

75 As previously stated, a great deal of difficulty

has heretofore been experienced in accurately positioning the panels and the like with respect to each other, and with respect to any supporting strips which were used in connection therewith. Also dust pockets were formed due to the angularity of the upper surface of any flange on which the panels were supported. The present invention obviates all these difficulties and provides a building structure and improved bulb-T element in which the elements are cheap to 10 manufacture and the completed structure is conveniently and easily assembled, and which will not easily get out of order when in use.

In the monolithic embodiment shown in Fig. 4, the plaster boards 14 or the like provide forms for the cementitious material and also become an integral part of the structure when the material sets.

Further modifications will be apparent to those skilled in the art and it is desired, therefore, that the invention be limited only by the prior art and the scope of the appended claims.

Having thus described my invention, what I claim and desire to secure by Letters Patent is:

1. A bulb-T member for building structures comprising a wide thin base, a thin vertical web terminating in a materially thicker bulb, said base having a longitudinal shoulder on each side of said web to provide stops for the edges of building panels supported on said base, the cross section through said stops and said web being greater than the cross section through said bulb so that the edge of each panel abutting a stop is outwardly spaced from the vertical plane of the adjacent side of said bulb sufficiently to allow sealing material to flow therebetween.

2. A bulb-T member for building structures comprising a wide thin base, a thin vertical web terminating in a materially thicker bulb, and reinforcing ribs at the intersection of said base and said web, said ribs forming longitudinal shoulders, the cross section of said ribs taken together with said web being greater than the cross section of said bulb so that, when panels of a thickness greater than the height of said bulb-T member are supported on the opposed base flanges with their edges abutting said shoulders, the edge of each panel will be spaced from the adjacent side of said bulb sufficiently to enable sealing material to flow therebetween and into the space below said bulb.

3. A building structure comprising a plurality of bulb-T strips supported in spaced relation, preformed panels of materially less length than the distance between the bulbs of adjacent strips and having their marginal edges supported on opposed strip flanges, said flanges having stops associated therewith and positioned relative to the sides of said bulb so that the edges of said panels abut said stops and are thereby laterally spaced outwardly from the vertical planes of adjacent bulbs to provide a sealing space between panel edges greater than the width of said bulb, and cementitious material completely filling the space between the edges of adjacent panels and between said panel edges and said strips.

4. A building structure comprising a plurality of bulb-T strips supported in spaced relation, preformed panels of materially less length than the distance between the bulbs of adjacent strips and having their marginal edges supported on opposed strip flanges, said flanges having stops associated therewith and positioned relative to the sides of said bulb so that the edges of said

panels abut said stops and are thereby laterally spaced outwardly from the vertical planes of adjacent bulbs to provide a sealing space between panel edges greater than the width of said bulb, and cementitious material completely filling the space between the edges of adjacent

panels and between said panel edges and said strips, said flanges being constructed to cause their marginal edges to maintain snug contact with said board and prevent dust pockets therebetween.
